ASSIGNORS TO BEEHLER STEEL PRODUCTS COMPANY, OF ST. LOUIS, MISSOURI, A CORPORATION OF MISSOURI.

BOX FASTENER.

1,402,759.

Specification of Letters Patent. Patented Jan. 10, 1922.

Application filed February 4, 1921. Serial No. 442,457.

To all whom it may concern:

Be it known that we, FREDERICK W. GOESSLING and JOHN M. GARRETT, citizens of the United States, residing in the city of St. Louis, State of Missouri, have invented a certain new and useful Improvement in Box Fasteners, of which the following is a full, clear, and exact description, such as will enable others skilled in the art to which it appertains to make and use the same.

This invention relates to box fasteners, and is an improvement on the box fastener shown in U. S. Patent No. 739,639, to C. W. Beehler, dated September 22, 1903.

The box fastener shown in said Beehler patent comprises a catch secured to the inner side of the front wall of a box at such a point that its upper end projects upwardly through a hole in the lid of the box when the lid is closed, a plate secured to the top side of the lid and provided with a raised central portion, and a spring housed in the raised central portion of the lid plate for co-operating with said catch and formed from a piece of spring wire that is doubled so as to form two diverging portions, one of which is provided with an upturned end that projects upwardly through a hole in the central raised portion of the lid plate. The upturned end of the catch engaging spring is relied upon to hold said spring in operative position in the raised portion of the lid plate, and accordingly, unless the user exercises considerable care, when moving the spring to disengage it from the catch, there is a tendency for the spring to twist in such a way that the upturned end of the spring will pull out of the hole in the lid plate and thus render the fastener inoperative.

The main object of our invention is to provide a box fastener of the same general construction as the box fastener shown in said Beehler patent, but which is so constructed that there is no liability of the spring twisting in such a way as to withdraw the upturned end of same from the hole in the lid plate during the operation of moving said spring to disengage it from the catch on the front wall of the box.

Another object is to provide a box fastener of the general character previously referred to in which the catch on the front

wall of the box is so constructed that the fastening devices which secure said catch in position will not be sheared, bent or pulled out of the front wall of the box in the event the upper end of said catch is subjected to a downward blow or to pressure tending to pull it away from the front wall of the box. Other objects and desirable features of our invention will be hereinafter pointed out.

Figure 1 of the drawing is a top plan view of a portion of the lid of a box equipped with a box fastener constructed in accordance with our invention.

Figure 2 is a front elevational view of a portion of the front wall, with the lid of the box broken away so as to more clearly illustrate the construction of the catch engaging spring.

Figure 3 is a view, looking at one end of the lid plate, showing the catch on the front wall of the box engaged by the spring on the lid plate; and

Figure 4 is a perspective view of the catch that is adapted to be secured to the front wall of the box.

Referring to the drawings which illustrate the preferred form of our invention, A designates the lid of a box, B the front wall of the box, C a catch that is adapted to be secured to the inner side of said front wall, D a plate that is adapted to be secured to the outer side of the lid A, and E a spring on said lid plate that co-operates with a hook 1 on the upper end of the catch C to retain the lid of the box in its closed position. The lid plate D is similar to the lid plate of the box fastener shown in the said Beehler patent and is provided with a raised central portion 2 which houses the spring E. Said spring is formed from a piece of spring wire that is bent to form two diverging portions, one of which is provided with an upturned end 3 that projects upwardly through a hole in the raised central portion 2 of the lid plate, the end of the other diverging portion of said spring being bent at 4, as shown in Figure 1, so as to bear against one end of the raised central portion 2 of the lid plate.

In order to prevent the catch engaging spring E from twisting or canting sufficiently to cause the upturned end 3 of same from pulling out of the central raised por-

tion 2 of the lid plate during the operation of moving said spring to disengage it from the catch C, we have provided the spring E with a portion F that bears upon the top side of the raised central portion 2 of the lid plate, and thus holds the two diverging portions of the spring in parallel relation with the lid plate at all times. As shown in Figures 1 and 2, the diverging portions of the catch engaging spring are connected to a finger piece G which projects over the raised central portion 2 of the lid plate, and the portion F, previously referred to, is preferably connected to the finger piece G. To release the spring E from the catch C the user places one finger against the finger piece G of the spring and exerts pressure on same in a direction away from the front wall of the box, thus causing the portion of the spring provided with the bent terminal 4 to move out of engagement with the hook 1 on the upper end of the catch C. The depending portion F on the finger piece bears upon the top side of the raised central portion 2 of the lid plate, and consequently, it is impossible for the spring F to twist or turn in such a manner as to pull the upturned end 3 of same out of the hole in the raised central portion 2 of the lid plate. Accordingly, such a box fastener is an improvement on the box fastener shown in the prior Beehler patent previously referred to, in that it is provided with means for preventing the catch engaging spring of same from becoming accidentally disconnected from the lid plate during the operation of actuating said spring to release it from the catch of the fastener. Moreover, as the spring E is provided with a raised finger piece G that can be grasped firmly by the fingers of the user, the lid of the box can be raised by lifting said finger piece upwardly, thereby enabling the lid of the box to be released and raised with one hand.

The catch C preferably consists of a sheet metal plate that is secured to the inner side of the front wall of the box by fastening devices 5, and in order to prevent said fastening devices from being sheared, bent or pulled loose from the front wall of the box in case the upper end of the catch C is subjected to a downward blow or to pressure in a direction tending to pull it away from the front wall of the box, we have provided said catch with laterally bent flanges or portions 6 that lap over the upper edge of the front wall of the box and which are secured to same by fastening devices 6^a that are driven into the upper edge of said front wall. The flanges 6 take up a downward strain or thrust on the projecting upper end portion of the catch, and the fastening devices 6^a which pass through said flanges counteract strains tending to force said catch rearwardly away from the front wall of the box.

Having thus described our invention, what we claim as new and desire to secure by Letters Patent is:

1. A box fastener consisting of a catch adapted to be secured to the wall of a box, a plate adapted to be secured to the lid of the box and having a raised central portion, a catch engaging spring located beneath the raised central portion of the lid plate and provided with a portion that projects upwardly through a hole in the raised central portion of the lid plate, and a part on said spring that bears upon the raised central portion of the lid plate and prevents said spring from assuming such a position that the upwardly projecting portion of same will accidentally pull out of the hole provided for same in the lid plate.

2. A box fastener, comprising a catch adapted to be secured to one of the vertical walls of a box, a plate adapted to be secured to the lid of the box, a housing on said lid plate, a spring arranged inside of said housing for co-operating with said catch and having a portion that projects through a hole in said housing, and a part on said spring that laps over said housing and bears against same in such a manner that the spring cannot twist or turn in such a way as to accidentally disengage it from the housing during the operation of moving the spring to release it from the catch.

3. A box fastener, comprising a catch adapted to be secured to the inner side of one of the upright walls of a box, a plate adapted to be secured to the lid of the box and provided with a raised central portion, a spring housed in said raised central portion and formed from a piece of spring wire that is bent to form two diverging portions that extend lengthwise of the lid plate, an upturned end on one portion of the spring that projects through a hole in the raised portion of the lid plate, and a finger piece at the opposite end of the spring provided with a portion that slides on the top side of the raised central portion of the lid plate and thus holds said spring in substantially parallel relation with the lid plate.

4. A box fastener, comprising a catch that is adapted to be secured to the inner side of one of the upright walls of a box, a plate adapted to be secured to the lid of the box and provided with a housing, a bent wire spring in said housing for co-operating with said catch and provided at one end with a portion that projects through a hole in said housing, and a part at the opposite end of said spring that projects over said housing and bears upon the outside face of the housing so as to prevent accidental disengagement of the spring from the housing.

5. A box fastener, comprising a catch adapted to be secured to the inner side of one of the upright walls of a box and pro-

vided with a part that laps over the upper edge of said wall, a plate on the lid of the box provided with a hole up through which said catch projects, a bent wire catch engaging spring interposed between said plate and the lid of the box and connected to said plate by a bent portion on one end of said spring that projects through a hole in said

plate, and a finger piece at the opposite end of said spring having a portion that slides 10 upon the exposed face of said lid plate during the operation of moving said spring to disengage it from said catch.
